UNITED STATES PATENT OFFICE

109,952

DESIGN FOR A MUSIC PORTFOLIO

Louis F. Stafford, Syracuse, N. Y.

Application September 9, 1937, Serial No. 71,524

Term of patent 3½ years

To all whom it may concern:

Be it known that I, Louis F. Stafford, a citizen of the United States, residing at Syracuse, in the county of Onondaga and State of New York, and having his post office address at 211 Slocum Avenue, Syracuse, New York, have invented a new, original, and ornamental Design for a Music Portfolio, of which the following is a specification, reference being had to the accompanying drawing forming part thereof.

The figure is a perspective view of a music portfolio showing my new design.

I claim:

The ornamental design for a music portfolio, substantially as shown.

LOUIS F. STAFFORD.
